UNITED STATES PATENT OFFICE

JOHN ADDISON CROWELL, OF WALLKILL, NEW YORK, ASSIGNOR TO JAMES B. CROWELL & SON, OF WALLKILL, NEW YORK, A CORPORATION OF NEW YORK

BRICK MOLD

Application filed July 14, 1930. Serial No. 467,731.

The present invention relates to brick molds, and more particularly to a novel and improved brick mold for use in the manufacture of brick by the "soft mud process" wherein clay material is forced through a die into a set of molds, and is an improvement on the mold illustrated, described and claimed in my prior and co-pending application, Serial No. 354,882, filed April 13, 1929.

10 These molds are principally constructed of wood, and are subjected to considerable pressure when the clay is forced out of a brick machine or press and into the molds.

In the manufacture of brick by the use of 15 said molds, either hand molds or such molds as are used in the present high speed and high pressure automatic brick machines, it is necessary to have vents along the bottom of each mold for each brick to permit the 20 air to be forced out of the mold as the clay is forced in, and to permit the clay—in a plastic condition—to flow fully into and completely fill the mold, particularly at the ends, corners, and sides of the bottom. Such 25 molds, however, must be made of considerable strength to withstand the pressure and beatings, and the vents as heretofore utilized were unsatisfactory because of necessarily weakening the mold structure, and also forming "fins" or the like on the brick, and often-times choking up.

A further difficulty with prior vents in molds has been that, due to the constant wetting and drying of the molds, and the consequent swelling and shrinking of the wood of the mold, the vents were constantly varying in size, thus preventing proper functioning of the mold. In my present invention I have devised a mold structure and vent which 40 gives great and increased strength, and which insures the complete filling of the corners, ends and sides, which insures an ample vent opening, and which furthermore insures a vent opening of constant size, irrespective of 45 the condition of the wood of the mold, whether wet or dry.

My novel mold will enable stiffer and better clay material to be put into the molds than has heretofore been possible.

50 The advantages of utilizing a stiffer clay

will be instantly apparent to those skilled in the art, as the resulting brick stand up better, prevent deformation, dry quicker, and burn more evenly and uniformly, thus improving the entire manufacture of the brick from the 55 pug mill to the kiln. The advantages of providing unvarying vent openings will also be apparent to those skilled in the art.

In carrying out my present invention I provide a metallic strap along the bottom of 60 each partition, said strap being wider than the partition and projecting beyond each bottom side of said partition in such a manner that at least one side of each vent opening will be defined by an edge of this metal strap. 65 Thus, any swelling or shrinking of the wood of the mold will have no effect on the size of the vent opening, which will remain constant in size whether the mold is dry or whether it is subjected to long and continuous moisture 70 or wetting. The metallic straps are so arranged in cooperation with the bottom panels that the said strap will be flush with the inner bottom surface of said panels and thus 75 will not mar, deform, or injure the brick in any way.

For example, assuming a mold to have individual molds 4 inches in width, and that partitions $\frac{5}{8}$ of an inch in width are utilized, the strap which I secure to the bottom of each 80 partition may be $\frac{1}{8}$ of an inch in width. Thus each strap will project outwardly from its partition $\frac{3}{2}$ of an inch on each side thereof. Each bottom panel will then be dadoed or grooved completely along each inner side. 85 The projecting portion of each strap will be seated in this dado, and will thus be flush with the inner surface of the bottom panel. If desired, I may make the bottom panel slightly wider than the width of the individual mold, so that the side edges of each panel will project under the partition, thus giving 90 a still stronger and more rigid mold structure.

Other features and objects of the invention 95 reside in the particular construction and arrangement of my novel mold.

The above and other objects and features of the invention, details of construction, combinations of parts, and advantages, will be 100

hereinafter more fully pointed out, described and claimed.

Referring to the drawings, illustrating a preferred embodiment of the invention,

5 Fig. 1 is a top plan view of a ten brick mold constructed in accordance with my invention;

Fig. 2 is a cross sectional view on the line 2—2 of Fig. 1;

10 Fig. 3 is a fragmentary longitudinal sectional view on the line 3—3 of Fig. 1;

Fig. 4 is a fragmentary perspective detail;

15 Fig. 5 is a partial bottom plan view of my novel mold;

Fig. 6 is a fragmentary longitudinal sectional view illustrating a modification;

Fig. 7 is a cross sectional view of said modification;

Fig. 8 is a fragmentary sectional perspective view of the modification of Figs. 6 and 7;

20 Fig. 9 is a view similar to Fig. 8, illustrating a modified form of bottom reenforcement; and

25 Fig. 10 is a view similar to Fig. 9, illustrating a still further modified form of bottom reenforcement.

Referring now to the drawings, for a particular description of the invention, it will be appreciated that the brick molds utilized in carrying out my invention may be of any suitable or desired number or size of brick. The invention may be embodied equally well in a hand sized mold for forming one, two or more bricks for hand dumping, handling and use, or in the present six, seven, eight or ten brick and more, for use in the modern high speed or automatic brick machines and presses, and it is in the latter field that my invention presents its greatest advantages. As herein illustrated, a ten brick mold is shown, such as is used in the present high speed or so-called automatic brick making machines, the mold illustrated comprising end blocks 1, sides 2, 2, partitions 3 and bottom panels 4.

35 These portions are constructed of wood, fastened in various ways, and usually bound with iron straps 5 and 6.

In carrying out my present invention, I provide in each panel 4, and at predetermined distances from the ends thereof, recesses 7, 50 these recesses extending a desired distance into the wood of the panel and being beveled downwardly and outwardly. Then along each side of the inner surface of the panels 4 I form a groove or dado 8, the recesses 7 extending into the inner surfaces of the panels beyond the dado. I then apply, along the bottom of each partition 3, a metallic strap 9, this strap 9 being affixed to the sides 2 and the dovetails on the partitions 3 by a screw 10 at each end of the strap 9.

55 It will be apparent from a glance at the drawings that each strap 9 projects beyond the partition 3 at each side thereof, and is seated in the dadoes 8. Thus, when the strap 9 is in position in the completed mold, the recesses

7 will project into the inner surfaces of the panels beyond the edge of said strap 9, forming vents 11 at each side of the bottom panel and adjacent to the ends thereof, while still being spaced from the partitions 3.

70 Thus, the forming of objectionable burrs or fins at the sides of the brick is eliminated.

Also, because of the fact that the straps 9 are rigidly fixed to the sides and partitions, and because said straps are seated in the dadoes 8, with the recesses 7 projecting beyond the straps 9, the size of the openings or vents 11 will remain substantially unchanged, regardless of the varying conditions of moisture or dryness to which the mold is subjected, thus insuring constant proper functioning of the mold under all conditions.

75 The outer edges of the straps 9 are flush with the inner surface of the panels 4, as clearly illustrated in the drawings. Thus, the size of the panels 4 is exactly the same as if made entirely of wood. The metallic straps 9 will also considerably reenforce and strengthen the panels 4, and thus will greatly strengthen the mold as a whole. Also, because of the fact that the straps 9 are affixed to the sides and partitions, instead of to the panels themselves, likelihood of splitting the panels by fastening devices is eliminated.

80 The number and size of the vents 11 may, of course, be varied, depending on the character or quality of the clay material being utilized, but regardless of original size, these vents will always remain constant and unvarying, being substantially unaffected by the "give and take" or swelling or shrinking of the wood of the mold. Thus the vent openings 11 will always be proportional to the work and clay for which the mold is intended, larger openings being suitable for higher speed operations and stiffer clay, or otherwise as desired or necessary.

85 In Figs. 6, 7 and 8 I have illustrated a slight modification of my invention, wherein the bottom panels 4 project under the partitions 3, at each side thereof, a narrow strap 12, preferably of metal, being fixed to the sides 2 and dovetails of the partitions 3 by screws 13. Slots 14 are cut or formed 90 through the panels 4 adjacent to each side thereof, and so arranged as to be spaced a slight distance from the partitions 3. Recesses 15 are formed on the under side of the panels 4, flaring away from the slots or vents 14 to eliminate clogging of said vents. I also utilize bottom straps 16, of slightly greater width than the width of the sides 2, so that said straps will afford a greater reenforcement than with straps of the same width as the sides 2, as heretofore utilized.

95 Furthermore, I am enabled to utilize screws or other fastening devices 17 which extend through the straps 16 into the panels 4, in addition to the screws 18 which secure

the straps 16 to the sides 2. In this form of the invention the slots 14 are spaced slightly, not only from the partitions 3, but also from the sides 2.

- 5 In Fig. 9 I have illustrated a modified form of bottom reenforcement, wherein two metallic straps or plates 19, preferably abutting of the center of the mold bottom are affixed to the sides 2 by screws 20 and to the 10 bottom panels by screws 21. These plates 19 are blocked out, as illustrated at 22, a distance equal to two of the recesses 15.

15 In Fig. 10 I have illustrated a single metallic plate 23 covering the entire bottom of the mold, secured to the sides of said mold by screws 24, and to the bottom panels 4 by screws 25, this plate being blocked out as illustrated at 26 to accommodate the recesses 15.

- 20 With each of the forms shown in Figs. 9 and 10 I am enabled to utilize thinner bottom panels, the straps or plates 19 and 23 reenforcing the mold to such an extent as to permit the utilization of thinner bottom 25 panels.

25 The metallic straps 12 affixed to the bottom of each partition 3 are of sufficient width to engage the sides of adjacent panels 4, and these straps 12 will thus also function to 30 prevent distortion or swelling of the bottom panels 4 when the mold is subjected to moisture.

35 Because of the retention and restraining of the bottom panels 4 by the straps 16, 19 and 23, there will be substantially no change in the size of the bottom panels, regardless of the conditions of moisture or dryness to which the mold is subjected.

- 40 While I have illustrated the bottom panels 4, in each form of the invention, as projecting under the partitions 3 to thus afford an additional support for the partitions, as well as the bottom panels, it will be appreciated that in the form of the invention illustrated 45 in Figs. 1 to 5 inclusive, the bottom panels need not project under the partitions 3, since the straps 9, being substantially an integral part of the partitions 3, will constitute ample support, but since these molds are subjected to considerable pounding, blows, 50 shocks and the like, I preferably extend the sides of the panels 4 under said partitions 3, in order to obtain all the support possible in these molds.

- 55 It will thus be instantly appreciated by those skilled in the art that I have devised an improved brick mold of this type and since I believe the same to be novel, I have, therefore, claimed said mold in the present 60 application.

While I have necessarily described my present invention somewhat in detail, it will be appreciated that I may vary the size, 65 shape, and arrangement of parts, within rea-

sonably wide limits, without departing from the spirit of the invention.

It will further be appreciated that, by 70 spacing the vents from the partitions and side walls of the mold, the sand which is placed in the molds prior to delivery of the clay therein, will not be blown away from the vicinity of the vents as is the case when the vents are formed closely adjacent to the partitions or side walls.

75 My invention is further described and defined in the form of claims as follows:

1. In a multi-brick mold, a wooden bottom panel completely covering the bottom of each individual mold, said panel having recesses 80 cut inwardly from the sides thereof at predetermined spaced intervals, the walls of said recesses flaring from the upper surface of said bottom panel outwardly, said panel having a recess extending longitudinally along the upper surface and at each side from end to end thereof, said first recesses projecting into the body of said panel beyond said second recesses, a plurality of partitions, and a metallic strap fixed to the bottom of each 85 partition, said strap being of greater width than the width of said partition and projecting beyond each side thereof, said strap being seated in the second recess of each panel of an adjacent pair of panels and constituting spacing means for said panels, that portion of said strap which is seated in said second recess being flush with the inner surface of said panel, said strap traversing said first recesses and closing all but a relatively small 90 amount thereof, said straps cooperating with said first recesses to form narrow vents in the inner surface of said panel, the edges of said strap forming one side of said vents.

95 2. In a multi-brick mold, a wooden bottom panel completely covering the bottom of each individual mold, said panel having recesses 100 cut inwardly from the sides thereof at predetermined spaced intervals, the walls of said recesses flaring from the upper surface of said bottom panel outwardly, said panel having a recess extending longitudinally along the upper surface and at each side from end to end thereof, said first recesses projecting into the body of said panel beyond said second recesses, a plurality of partitions, a metallic strap fixed to the bottom of each partition, said strap being of greater width than the width of said partition and projecting beyond each side thereof, said strap being seated in the second recess of each panel of an adjacent pair of panels and constituting spacing means for said panels, that portion of said strap which is seated in said second recess being flush with the inner surface of 110 said panel, said strap traversing said first recesses and closing all but a relatively small amount thereof, said straps cooperating with said first recesses to form narrow vents in the inner surface of said panel, the edges of said strap forming one side of said vents.

115 3. In a multi-brick mold, a wooden bottom panel completely covering the bottom of each individual mold, said panel having recesses 120 cut inwardly from the sides thereof at predetermined spaced intervals, the walls of said recesses flaring from the upper surface of said bottom panel outwardly, said panel having a recess extending longitudinally along the upper surface and at each side from end to end thereof, said first recesses projecting into the body of said panel beyond said second recesses, a plurality of partitions, a metallic strap fixed to the bottom of each partition, said strap being of greater width than the width of said partition and projecting beyond each side thereof, said strap being seated in the second recess of each panel of an adjacent pair of panels and constituting spacing means for said panels, that portion of said strap which is seated in said second recess being flush with the inner surface of 125 said panel, said strap traversing said first recesses and closing all but a relatively small amount thereof, said straps cooperating with said first recesses to form narrow vents in the inner surface of said panel, the edges of said 130 strap forming one side of said vents.

strap forming one side of said vents, and means to rigidly attach said straps to said partitions.

3. In a multi-brick mold, a wooden bottom panel completely covering the bottom of each individual mold, said panel having vents therein adjacent to the sides thereof at predetermined spaced intervals, a plurality of partitions, and a metallic strap fixed to the bottom of each partition and constituting spacing means for said panels.

In testimony whereof, I have signed my name to this specification.

J. ADDISON CROWELL.
